UNITED STATES PATENT OFFICE.

PHILIP FISCHBACHER, OF QUINCY, ILLINOIS.

REFRIGERATING APPARATUS.

Application filed February 2, 1920. Serial No. 355,734.

To all whom it may concern:

Be it known that I, PHILIP FISCHBACHER, a citizen of the United States, residing at Quincy, in the county of Adams and State of Illinois, have invented certain new and useful Improvements in Refrigerating Apparatus, of which the following is a specification.

This invention relates to refrigerating plants.

One object of the invention is to provide a simple, compact, relatively inexpensive, and efficient refrigerating plant wherein the cost of the refrigerating process is reduced to a minimum.

Another object is to provide simple and efficient means whereby the temperature of the condensing medium is automatically maintained within certain predetermined limits.

Another object is to provide a simple and efficient double-cylinder, double-acting compressor wherein stuffing boxes are eliminated.

Another object is to provide a simple refrigerating plant wherein the number of parts is reduced to a minimum and are simple in themselves, and which cooperate in a manner to meet all the requirements for successful commercial operation.

These and other objects are accomplished by means of the arrangement disclosed on the accompanying sheets of drawings, in which—

Figure 1 is a view somewhat diagrammatic in form and in part being a vertical sectional view of the apparatus.

Figure 2 is a top plan view of the same, omitting the main part of the evaporating coil; and

Figure 3 is an enlarged sectional view of the water regulating valve.

The various novel features of my invention will be apparent from the following description and drawings, and will be particularly pointed out in the appended claims.

Referring to the figures of the drawings, it will be noted that I have disclosed a refrigerating plant including a fluid compressor which has two adjacently arranged parallel cylinders 10 and 11 formed integrally in a single block. Mounted in these cylinders for reciprocation therein are two pistons 12 and 13 which are connected to each other and to a single connecting rod 14 by

a single wrist pin 15. The inner adjacent walls of the cylinders 10 and 11 are provided with elongated openings 16 and 17 which are sufficiently long to permit the full stroke of the pistons without any interference whatsoever to the movement of the wrist pin which moves therein. Each of the pistons is provided with four piston rings 18 to make the same substantially fluid tight within the cylinders. Located at each end of each of the cylinders is a valve 19, the valve in each case having a stem 20 slidably and guidably mounted in an apertured boss 21 formed on the inner side of a cylinder cover 22. The cylinder cover in each case preferably is screwed into the ends of the cylinder. Surrounding the boss 21 and pressing against the valve 19 for normally maintaining the same in a closed position is a coil spring 23. The upper central portion 24 of the integrally-formed cylinders is provided with an inlet opening 25 in communication with one end 25' of an evaporating coil 26. The cylinder inlet opening 25 opens into the central chamber 27 intermediate the cylinders 10 and 11. Formed in the inner walls 28 of the cylinders at two different points along the lengths of the cylinders are a plurality of apertures 29 which connect the chamber 27 with the compression chambers of the cylinders. It is apparent, therefore, that when the pistons are drawn into their downward position, as shown in Figure 1 of the drawings, gas from the evaporating coil is drawn therefrom through chamber 27, upper apertures 29, into the upper compression chambers of the cylinders, it being understood that the apertures or upper ports 29 at this time are uncovered. On the upward stroke of the pistons the apertures or ports 29 will be covered by the pistons and the gas in the upper ends of said cylinders compressed, causing, at the proper instant, the upper valves 19 to open against the tension of the springs 23, the compressed refrigerating agent then passing outwardly through a pipe connection 30 in the form of a gas or liquid, or both, into a relatively large annular integrally-formed condenser 31, which surrounds and is spaced from the centrally located cylinders 10 and 11. This condenser preferably is in one piece and is made of steel. By making the condenser in the form shown, cracks in the material are avoided, and accordingly leakage is avoided. Much trouble encountered

with the coil type of condenser is thereby eliminated. In this condenser the discharged gases of the refrigerating agent are converted from a gas to a liquid form preparatory to passing into the receiver, to be mentioned hereinafter. It will be understood that as the pistons are moved upwardly, not only do they compress the refrigerating agent in the upper compressor chambers of the cylinders, but also at the same time when the lower apertures or ports 29 are uncovered, the gas or refrigerating agent is drawn from the central chamber 27 through the said apertures 29 into the lower compression chambers of the two cylinders. Accordingly, when the pistons are moved downwardly, the refrigerating agent in the lower compression chambers of the pistons is compressed and forced outwardly through the lower valves 19 and upwardly through passageways 32 in the cylinder block, and through the same pipe connections 30 into the same condenser 31. The discharge or outlet valves 19 have a diameter equal to the diameter of the cylinder bores so that if any liquid or other foreign matters are formed or pass into the compression chambers of the cylinder, no injury will be done to the head of the cylinders as a large free discharge passage is provided. It will be seen, therefore, that this refrigerating machine includes the double-cylinder, double-acting compressor or fluid engine, the pistons of which are actuated through the single wrist pin 15 and connecting rod 14, which in this case terminates in an eccentric strap 33 surrounding an eccentric 34 mounted upon one end of the main drive shaft 35, which has mounted thereon a worm gear 36 driven by a worm 37, the shaft 35 being mounted in a bearing or sleeve 38 preferably formed integrally with the base or crank case 39 of the machine, and one end of the shaft being mounted in an end bearing 40 formed integrally with a side cover 41 for the base secured thereto by any suitable means. Of course, it will be appreciated that the connecting rod may be driven by any other suitable mechanism, but in any event, it will be noted that the use of stuffing boxes in connection with the cylinders has been entirely eliminated, thereby overcoming leakages of the refrigerating medium therethrough, especially on the high pressure side. At this point it may be stated that the integrally-formed cylinders are mounted upon the crank case or base 39 by means of a tongue and groove arrangement 42 made tight by lead gaskets therein, the crank case and cylinders being rigidly held to each other by any suitable means, such as bolts 43. The two chambers 44 and 45 within the crank case 39 are full of oil and grease to cover all bearings and working parts of the compressor. Accordingly, not

only are the parts well lubricated thereby, but as a result of this arrangement no air can be drawn into said chambers when same are under vacuum. This results in a machine practically air-tight. 70

From an inspection of Figures 1 and 2 it will be noted that the incoming gases have contact with the walls 28, 28 of the compression cylinders throughout substantially the full length of said cylinders and 75 throughout a considerable portion of the peripheries of said cylinders. By reason of this construction the incoming gases serve to cool the gases under compression, thereby saving considerable effort in compressing said gases and permitting a reduction in the condenser. 80

It will be noted also that the pistons 12, 13 operate the valves 19, 19 by engaging the inner sides of said valves, whereby, 85 when said pistons 12, 13 engage said valves they carry said valves along with them in the opening operation of said valves. When said pistons move in directions to permit the closing of the valves 19, 19 said valves 90 follow said pistons in close contact therewith until said valves become seated. By reason of this construction, all the gases are expelled from the cylinders after compression, whereby no compressed gases remain when the intake stroke begins. This structure is of advantage inasmuch as troubles due to expansion of unexpelled gases are eliminated and the efficiency of compressors as now commonly known and 95 used is improved upon. 100

In combination with the advantages above noted is the advantage that the structure according to the present invention retains the advantage and efficiency of double acting pistons, but does this without stuffing boxes and without reducing the effective area of either piston by the cross-sectional area of a piston rod. 105

The refrigerating agent is pressed into the 110 condenser 31 for the purpose of being condensed into a liquid. To facilitate the condensing of the fluid the condenser is mounted within a casing 46 which is secured to the crank case 39 in any suitable manner to make 115 a water-tight joint at 47 between the parts in question. This casing 46 forms a water jacket for the condenser, it being understood that water will surround all parts of the condenser and compressor cylinders and 120 will be maintained at the level of the overflow or waste pipe 48. For example, while the pressure of the refrigerating agent may be at about five pounds per square inch in the evaporating coil 26, which forms a part 125 of the low pressure side of the system, the pressure of the refrigerating agent in the condenser, which forms a part of the high pressure side of the system will be, for example, at about one hundred fifty pounds 130

per square inch. It is desirable, of course, to maintain the pressure and temperature of the refrigerating agent in the condenser within certain predetermined limits. Accordingly, the condensing fluid or water within the casing 46 must be maintained sufficiently low in temperature at all times to be effective for condensing the refrigerating agent in the condenser 31. Normally, the body of condensing water in the casing 46 is at rest. However, to maintain the water in said casing at an efficient condensing temperature, at times relatively cold water must be supplied to said casing. I have provided means for automatically controlling the supply of cold water to the casing, said means comprising a regulating valve 49, which is in communication with the lower end of the condenser through a pipe 50. Mounted within the casing 51 of the valve 49 is a diaphragm 52, the upper side of which is exposed to the pressure within the condenser 31 and the lower side of which is engaged by an enlarged plate-like portion 53 of a valve stem 54, the lower end of which terminates in a valve 55 which controls communication between an inlet cold water pipe 56 and a cold water supply pipe 57 extending between the valve 49 and the casing 46. Properly graduated springs 58 and 59 operate on the valve 55 and its stem on one side of the diaphragm 52, so that only when the pressure within the condenser 31 rises above a predetermined point does the valve 55 open to automatically permit the supply of cold water to the casing 46, whereupon the temperature within the condenser, and therefore the pressure, fall, whereupon the valve 55 is automatically closed to prevent for the time being a further supply of cold water to the casing 46. It will be understood that the relatively warm water in the upper part of the casing 46 will flow off through the overflow pipe 48. The pipe 50 has a valve 60 for controlling any communication or pressure between the condenser 31 and the regulating valve 49. At this point I wish to mention the fact that any oil which is transmitted through the system is collected in the bottom of the condenser 31, and to drain this oil out of the system I have provided a connection 61 between the pipe 50 and the oil chamber 44, whereby when the valve 62 in the connection 61 is open, the oil at the bottom of the condenser will be forced under pressure through the pipes 51 and 61 into the oil chamber 44. The refrigerating agent is passed from the condenser in the form of a liquid through the pipe 63 into a liquid receiver 64. If for any reason any part of the refrigerating agent takes the form of a gas within the liquid receiver 64, such gas is passed back into the upper end of the condenser through an equalizing pipe 65, thereby equalizing the pressure in the receiver and condenser. This liquid receiver preferably is mounted upon the base plate of the apparatus and forms a part of the unit. It will be understood that the pressure of the refrigerating agent in the liquid receiver is relatively high. The high pressure side of the system is connected to the low pressure side thereof through any suitable automatic expansion valve 66, the liquid which passes through the expansion valve 66 immediately expanding and being transformed into a gas which passes through a pipe 67 entering the upper end of the evaporating coil 26, wherein the gas further expands. As is well understood in the art, the gas within the evaporating coil is at a very low temperature. For example, where ammonia is used with a five-pound pressure of gas within the evaporating coil, the temperature of said gas will be 15° below zero. This evaporating coil 26 may be located in a compartment of an ice box, and, as a matter of fact, the whole refrigerating unit may be mounted within ice boxes varying from small to large units, in accordance with requirements. From what has been stated hereinabove, it is appreciated that as the pistons 12 and 13 are actuated within their cylinders, the low pressure gas in the evaporating coil 26 is drawn into the cylinders and compressed and forced into the condenser where such gases are recondensed and put under high pressure, whereupon they are passed into the liquid receiver and then out through the pipe 67 back into the evaporating coil, completing the refrigerating cycle.

I claim:

1. In a compressor, the combination of adjacently arranged cylinders having a space therebetween, double acting pistons mounted for reciprocating movement in said cylinders, a pin connecting said pistons, means for communicating refrigerant to said space, a driving member connected to said pin and movably mounted in said space, and a lubricating medium for said driving member forming a seal to prevent ingress of air from the outside of said compressor to said space.
2. In refrigerating apparatus, in combination, a crank case containing lubricating medium, compression cylinders mounted upon and closely sealed to said crank case, double acting pistons in said cylinders, driving means for said cylinders mounted in said crank case, means providing an inlet chamber between said cylinders, driving means extending from said crank case into said chamber and connected to said pistons, said lubricating medium being located at a level to form a seal against ingress of air from the outside of said apparatus to said chamber, ports being provided for the admission of refrigerant from said chamber.

to said cylinder on the two sides of said pistons, said ports being positioned to be selectively covered and uncovered in reciprocation of said piston.

5. 3. In a refrigerating plant, means providing a pair of parallel cylinders having a chamber therebetween for the admission of refrigerant, double acting pistons in said cylinders and driving means in said chamber for communicating motion to said pistons, a crank case, said cylinders being mounted upon and sealed to said crank case, mechanism within said crank case for actuating said driving means, and lubricant within said crank case for preventing the passage of gas from said cylinders through said crank case.

4. In a refrigerating plant, in combination, means providing a pair of parallel cylinders and a chamber therebetween for the admission of refrigerant, a crank case, double acting pistons in said cylinders, driving means in said chamber for com-

municating motion to said pistons, said means being mounted upon and sealed to 25 said crank case, means within said crank case for actuating said driving means, and lubricant within said crank case for acting as a seal between said cylinders and the outside air.

5. In a refrigerating plant, in combination, means providing a pair of cylinders having a chamber therebetween for the admission of refrigerant, double acting plungers in said cylinders, said cylinder being provided with common driving means, a crank case, said first mentioned means being mounted upon and sealed to said crank case, said crank case being provided with means for actuating said common driving 40 means and being provided with lubricant to constitute a seal between said cylinders and the outside air.

Signed at Chicago, Illinois, this 20th day of January, 1920.

PHILIP FISCHBACHER
